(57) **ABSTRACT**

A unit attachment-detachment mechanism includes a unit and a pair of guide rails. The pair of guide rails slidably supports a pair of side faces of the unit. The side faces respectively have formed thereon engagement projections that engage with the guide rails. The pair of guide rails has formed therein at least a pair of inclined portions. The pair of inclined portions is formed asymmetrically with each other in the unit width direction perpendicular to the attachment-detachment direction.

**UNIT ATTACHMENT-DETACHMENT
MECHANISM AND IMAGE FORMING
APPARATUS THEREWITH**

INCORPORATION BY REFERENCE

This application is based upon and claims the benefit of priority from the corresponding Japanese Patent Application No. 2016-090872 filed on Apr. 28, 2016, the entire contents of which are incorporated herein by reference.

BACKGROUND

The present disclosure relates to a unit attachment-detachment mechanism including a unit attachable to and detachable from an apparatus main body and a pair of guide rails slidably supporting the unit, and also relates to an image forming apparatus incorporating such a unit attachment-detachment mechanism.

Conventionally, in an image forming apparatus relying on an electrophotographic process, a fixing unit, a drum unit, a developing unit, an intermediary transfer unit, and the like are fixed with screws in predetermined positions inside the image forming apparatus. On the other hand, when a sheet that has stuck (a jam) is dealt with, those units need to be taken out of the main body of the image forming apparatus. Also, if any unit has a service life shorter than that of the image forming apparatus, it needs to be replaced regularly.

With the conventional configuration mentioned above, every time a unit needs to be replaced or a stuck sheet (a jam) needs to be dealt with, a serviceperson has to be sent for, resulting in low efficiency. On the other hand, for a non-professional user, attaching or detaching a unit using tools is a great burden. Against this background, there have been proposed methods that allow a user easy replacement of units, and according to a widely adopted configuration, a unit is inserted and pulled out along a guide shape provided in the main body of an image forming apparatus.

For example, in one known image forming apparatus, there are provided an intermediary transfer unit and a pair of guide rails that slidably supports engagement projections on side faces of the intermediary transfer unit. The intermediary transfer unit, when attached to the apparatus main body, has to be in contact with a drum unit but, in the middle of being attached or detached, has to be out of contact with the drum unit, a developing unit, and the like. Thus, to permit the intermediary transfer unit to move in the up-down direction (in the direction away from the drum unit), the guide rails have inclined portions.

SUMMARY

According to one aspect of the present disclosure, a unit attachment-detachment mechanism includes a unit and a pair of guide rails. The unit is attachable to and detachable from an apparatus main body in the horizontal direction. The pair of guide rails is provided on the apparatus main body, and slidably supports a pair of side faces of the unit that are parallel to the attachment-detachment direction of the unit. The side faces respectively have formed on them engagement projections that engage with the guide rails. The pair of guide rails has formed in them at least a pair of inclined portions along which the engagement projections move in the up-down direction. The pair of inclined portions is formed asymmetrically with each other in the unit width direction perpendicular to the attachment-detachment direction.

2

Further features and advantages of the present disclosure will become apparent from the description of embodiments given below.

5 BRIEF DESCRIPTION OF THE DRAWINGS

FIG. 1 is a schematic sectional view showing the structure of an image forming apparatus incorporating a unit attachment-detachment mechanism according to a first embodiment of the present disclosure;

10 FIG. 2 is a perspective view showing the structure of the unit attachment-detachment mechanism according to the first embodiment of the present disclosure;

15 FIG. 3 is a perspective view showing the structure of an intermediary transfer unit in the unit attachment-detachment mechanism according to the first embodiment of the present disclosure;

20 FIG. 4 is a plan view showing the structure of the intermediary transfer unit in the unit attachment-detachment mechanism according to the first embodiment of the present disclosure;

25 FIG. 5 is a perspective view showing the structure of a pair of support frames in the unit attachment-detachment mechanism according to the first embodiment of the present disclosure;

FIG. 6 is a diagram showing the structure of a support frame 41 in the unit attachment-detachment mechanism according to the first embodiment of the present disclosure;

30 FIG. 7 is a diagram showing the structure of a support frame 42 in the unit attachment-detachment mechanism according to the first embodiment of the present disclosure;

35 FIG. 8 is a diagram showing the structure of the support frame 42 in the unit attachment-detachment mechanism according to the first embodiment of the present disclosure as seen from the near side of the plane of FIG. 5, with first and second inclined portions in the support frame 41 superimposed;

40 FIG. 9 is a diagram showing the structure of the support frame 42 in the unit attachment-detachment mechanism according to the first embodiment of the present disclosure as seen from the near side of the plane of FIG. 5, with third inclined portions in the support frame 41 superimposed;

45 FIG. 10 is a diagram showing the structure of a support frame 42 in a unit attachment-detachment mechanism according to a second embodiment of the present disclosure as seen from the near side of the plane of FIG. 5, with first and second inclined portions in a support frame 41 superimposed; and

50 FIG. 11 is a diagram showing the structure of the support frame 42 in the unit attachment-detachment mechanism according to the second embodiment of the present disclosure as seen from the near side of the plane of FIG. 5, with third inclined portions in the support frame 41 superimposed.

55 DETAILED DESCRIPTION

Embodiments of the present disclosure will be described below with reference to the accompanying drawings.

60 First Embodiment

65 FIG. 1 is a schematic sectional view showing the configuration of an image forming apparatus 100 incorporating a unit attachment-detachment mechanism 50 according to a first embodiment of the present disclosure, and depicts a tandem-type color image forming apparatus. Inside the main

body of the image forming apparatus 100, four image forming sections Pa, Pb, Pc, and Pd are arranged in this order from the upstream side (in FIG. 1, the left side) in the conveying direction. These image forming sections Pa to Pd are provided to correspond to four different colors (cyan, magenta, yellow, and black), and form cyan, magenta, yellow, and black images successively each through the processes of charging, exposure, development, and transfer.

In these image forming sections Pa to Pd, photosensitive drums 1a, 1b, 1c, and 1d that carry visible images (toner images) of the different colors are arranged, and an intermediary transfer belt 8 that rotates counter-clockwise in FIG. 1 by being driven by a driving means (unillustrated) is provided next to the these image forming sections Pa to Pd. The toner images formed on these photosensitive drums 1a to 1d are successively transferred to the intermediary transfer belt 8, which moves while in contact with the photosensitive drums 1a to 1d, so as to be superimposed on each other, and are then transferred, by the action of a secondary transfer roller 9, to a transfer sheet P as one example of a recording medium, and are then fixed to the transfer sheet P in a fixing unit 13, the sheet then being discharged out of the apparatus main body. While the photosensitive drums 1a to 1d are rotated clockwise in FIG. 1, an image forming process is performed with respect to the photosensitive drums 1a to 1d.

Transfer sheets P to which toner images are to be transferred are stored in a sheet cassette 16 in a lower part of the apparatus, and are transferred, via a sheet feed roller 12a and a pair of registration rollers 12b, to a nip portion between the secondary transfer roller 9 and a driving roller 11, which will be described later, of the intermediary transfer belt 8. For the intermediary transfer belt 8, a sheet of a dielectric resin is used, which typically is a belt with no seam (a seamless belt). On the downstream side of the secondary transfer roller 9, a blade-form belt cleaner 19 for removing the toner that is left behind on the surface of the intermediary transfer belt 8 is arranged.

Next, the image forming sections Pa to Pd will be described. Around and under the photosensitive drums 1a to 1d, which are rotatably arranged, there are provided chargers 2a, 2b, 2c, and 2d for electrostatically charging the photosensitive drums 1a to 1d, an exposure device 5 for exposing the photosensitive drums 1a to 1d to light of image information, developing devices 3a, 3b, 3c, and 3d for forming toner images on the photosensitive drums 1a to 1d, and cleaning devices 7a, 7b, 7c, and 7d for removing the developer (toner) that is left behind on the photosensitive drums 1a to 1d.

When image data is entered from a host device such as a personal computer, first, by the chargers 2a to 2d, the surfaces of the photosensitive drums 1a to 1d are electrostatically charged uniformly, and then by the exposure device 5, light is radiated according to image data so that, on the photosensitive drums 1a to 1d, electrostatic latent images corresponding to the image data are formed. The developing devices 3a to 3d are charged with predetermined amounts of two-component toner containing toner of different colors, namely cyan, magenta, yellow, and black, respectively. When the proportion of the toner in the two-component developer contained in the developing devices 3a to 3d falls below a prescribed value, toner is supplied from toner containers 4a to 4d to the developing devices 3a to 3d. The toner in the developer is fed onto the photosensitive drums 1a to 1d by the developing devices 3a to 3d and, by electrostatically attaching to them, forms the toner images

corresponding to the electrostatic latent images formed by exposure to the light from the exposure device 5.

Then, by applying a predetermined transfer voltage to primary transfer rollers 6a to 6d, the cyan, magenta, yellow, and black toner images on the photosensitive drums 1a to 1d are primarily transferred to the intermediary transfer belt 8. These images of the four colors are formed in a predetermined positional relationship that is previously determined for the formation of a predetermined full-color image.

10 Thereafter, the toner and the like that are left behind on the surfaces of the photosensitive drums 1a to 1d are removed by the cleaning devices 7a to 7d in preparation for the subsequent formation of new electrostatic latent images.

The intermediary transfer belt 8 is stretched between a 15 driven roller 10, on the upstream side, and a driving roller 11, on the downstream side, and when the intermediary transfer belt 8 starts to rotate counter-clockwise as the driving roller 11 rotates by being driven by a driving motor (unillustrated), a transfer sheet P is conveyed, with predetermined timing, from the pair of registration rollers 12b to a 20 nip portion (secondary transfer nip portion) between the driving roller 11 and the secondary transfer roller 9, the latter being provided next to the former, so that the full-color image on the intermediary transfer belt 8 is transferred to the 25 transfer sheet P. The sheet P having the toner images transferred to it is conveyed through a sheet conveying passage 18 to the fixing unit 13.

The transfer sheet P conveyed to the fixing unit 13 is heated and pressed by a pair of fixing rollers 13a, so that the 30 toner images are fixed to the surface of the transfer sheet P, forming the predetermined full-color image. The transfer sheet P having the full-color image formed on it is distributed between different conveying directions by a branch portion 14 which branches into a plurality of directions. 35 When an image is formed on only one side of the sheet P, it is discharged as it is onto a discharge tray 17 by a discharge roller 15.

On the other hand, when an image is formed on each side of the sheet P, the sheet P having passed through the fixing 40 unit 13 is first conveyed toward the discharge roller 15, and when the tail end of the sheet P has passed through the branch portion 14, the discharge roller 15 is rotated reversely, and the conveying direction of the branch portion 14 is so switched that the sheet P is, starting with its tail end, 45 distributed to a two-sided conveying passage 20, the sheet P then being conveyed once again, with the image side reversed, to the secondary transfer nip portion. Then, the next image formed on the intermediary transfer belt 8 is transferred by the secondary transfer roller 9 to the side of the sheet P on which no image has yet been formed, and the sheet P is then conveyed to the fixing unit 13, where the toner images are fixed, and is then discharged onto the discharge tray 17.

FIG. 2 is a perspective view showing the structure of the 55 unit attachment-detachment mechanism 50 according to the first embodiment of the present disclosure, FIG. 3 is a perspective view showing the structure of an intermediary transfer unit 30 in the unit attachment-detachment mechanism 50 according to the first embodiment of the present disclosure, FIG. 4 is a plan view showing the structure of the 60 intermediary transfer unit 30 in the unit attachment-detachment mechanism 50 according to the first embodiment of the present disclosure, and FIG. 5 is a perspective view showing the structure of a pair of support frames 41 and 42 in the unit attachment-detachment mechanism 50 according to the first embodiment of the present disclosure. FIGS. 2 and 3 are views seen from the far side of the plane of FIG. 1.

As shown in FIGS. 2 to 4, the intermediary transfer unit 30 is composed of a unit body 34 which is composed of two side frames (side faces) 31 and 32 and a top frame 33, primary transfer rollers 6a to 6d, the driven roller 10, and the driving roller 11 (for these, see FIG. 1) which are supported between the side frames 31 and 32, the endless intermediary transfer belt 8 which is stretched around those rollers, and the like.

On the side frames 31 and 32, there are provided first bosses 31a and 32a and second bosses 31b and 32b which are engagement projections that engage with a pair of support frames 41 and 42 (see FIGS. 2 and 5) which are provided in the main body of the image forming apparatus 100. The first bosses 31a and 32a are formed in the same size, and are arranged at the same position and at the same height in the attachment-detachment direction (the direction indicated by arrows AA') of the intermediary transfer unit 30. Likewise, the second bosses 31b and 32b are formed in the same size, and are arranged at the same position and at the same height in the attachment-detachment direction (the direction indicated by arrows AA', the horizontal direction) of the intermediary transfer unit 30. The intermediary transfer unit 30 and the pair of support frames 41 and 42 constitute the unit attachment-detachment mechanism 50. The pair of support frames 41 and 42 is supported so as to be attachable to and removable from the main body of the image forming apparatus 100.

As shown in FIGS. 6 and 7, on the pair of support frames 41 and 42, there is provided a pair of guide rails 41a and 42a which slidably support the first bosses 31a and 32a and the second bosses 31b and 32b on the intermediary transfer unit 30. The guide rails 41a and 42a are formed in the shape of grooves that hold the first bosses 31a and 32a and the second bosses 31b and 32b from above and below so as to restrict their movement in the up-down direction.

In the guide rails 41a and 42a, there are provided, from the upstream side (in the direction indicated by arrow A') of the attachment direction of the intermediary transfer unit 30, first flat portions 41b and 42b, first inclined portions 41c and 42c, second flat portions 41d and 42d, second inclined portions 41e and 42e, third flat portions 41f and 42f, third inclined portions 41g and 42g, and fourth flat portions 41h and 42h.

The first flat portions 41b and 42b are open on the upstream side (in the direction indicated by arrow A') in the unit attachment direction and on the top side so as to receive the first bosses 31a and 32a and the second bosses 31b and 32b easily. The first inclined portions 41c and 42c are arranged in a part of the guide rails 41a and 42a on the upstream side in the unit attachment direction, and are inclined downward toward the downstream side (in the direction indicated by arrow A) of the unit attachment direction. The second flat portions 41d and 42d are arranged lower than the first flat portions 41b and 42b and the third flat portions 41f and 42f. The second inclined portions 41e and 42e are arranged in a part of the guide rails 41a and 42a on the upstream side of the unit attachment direction, and are inclined upward toward the upstream side of the unit attachment direction. The third flat portions 41f and 42f are arranged at the same height as the first flat portions 41b and 42b. The third inclined portions 41g and 42g are arranged at an end part of the guide rails 41a and 42a on the downstream side in the unit attachment direction, and are inclined downward toward the downstream side in the unit attachment direction. The fourth flat portions 41h and 42h are arranged lower than the second flat portions 41d and 42d.

Here, the first inclined portions 41c and 42c are formed asymmetrically with each other in the unit width direction (the up-down direction in FIG. 4) perpendicular to the unit attachment-detachment direction, so are the second inclined portions 41e and 42e, and so are the third inclined portions 41g and 42g.

In this embodiment, the first inclined portions 41c and 42c are arranged at mutually different positions in the unit attachment-detachment direction (the direction indicated by arrows AA'), so are the second inclined portions 41e and 42e, and so are the third inclined portions 41g and 42g. Specifically, as shown in FIG. 8, the first inclined portion 41c is arranged with a displacement of about several millimeters to the upstream side (in the direction indicated by arrow A') in the unit attachment direction relative to the first inclined portion 42c. Likewise, the second inclined portion 41e is arranged with a displacement of about several millimeters to the upstream side (in the direction indicated by arrow A') in the unit attachment direction relative to the second inclined portion 42e, and, as shown in FIG. 9, the third inclined portion 41g is arranged with a displacement of about several millimeters to the upstream side (in the direction indicated by arrow A') in the unit attachment direction relative to the third inclined portion 42g.

When the intermediary transfer unit 30 is attached to the main body of the image forming apparatus 100, the first bosses 31a and 32a on the intermediary transfer unit 30 pass through the first flat portions 41b and 42b, the first inclined portions 41c and 42c, the second flat portions 41d and 42d, the second inclined portions 41e and 42e, and the third flat portions 41f and 42f of the guide rails 41a and 42a in the order named. Meanwhile, since the first inclined portion 41c is arranged on the upstream side (in the direction indicated by arrow A') in the unit attachment direction relative to the first inclined portion 42c, the first boss 31a moves downward with advanced timing relative to the first boss 32a. Thus, with the intermediary transfer unit 30 in a slightly twisted state, the first bosses 31a and 32a pass through the first inclined portions 41c and 42c. Since the second inclined portion 41e is arranged on the upstream side (in the direction indicated by arrow A') in the unit attachment direction relative to the second inclined portion 42e, the first boss 31a moves upward with advanced timing relative to the first boss 32a. Thus, with the intermediary transfer unit 30 in a slightly twisted state, the first bosses 31a and 32a pass through the second inclined portions 41e and 42e.

While the first bosses 31a and 32a are passing through the third flat portions 41f and 42f, the intermediary transfer belt 8 is located away from the photosensitive drums 1a to 1d. When the first bosses 31a and 32a reach an end part of the third flat portions 41f and 42f on the downstream side (in the direction indicated by arrow A) in the unit attachment-detachment direction, the second bosses 31b and 32b are located in the first flat portions 41b and 42b.

When the intermediary transfer unit 30 is pushed further in the attachment direction (the direction indicated by arrow A), the first bosses 31a and 32a pass through the third inclined portions 41g and 42g. Meanwhile, since the third inclined portion 41g is arranged on the upstream side (in the direction indicated by arrow A') in the unit attachment direction relative to the third inclined portion 42g, the first boss 31a moves downward with advanced timing relative to the first boss 32a. Thus, with the intermediary transfer unit 30 in a slightly twisted state, the first bosses 31a and 32a pass through the third inclined portions 41g and 42g.

When the first bosses 31a and 32a have passed through the third inclined portions 41g and 42g and reached the

fourth flat portions **41h** and **42h**, the second bosses **31b** and **32b** are located in the first flat portions **41b** and **42b**. As the first bosses **31a** and **32a** move through the fourth flat portions **41h** and **42h** in the attachment direction (the direction indicated by arrow A), the second bosses **31b** and **32b** pass through the first inclined portions **41c** and **42c** and are located in the second flat portions **41d** and **42d**. Meanwhile, since the first inclined portion **41c** is arranged on the upstream side (in the direction indicated by arrow A') in the unit attachment direction relative to the first inclined portion **42c**, the second boss **31b** moves downward with advanced timing relative to the second boss **32b**. Thus, with the intermediary transfer unit **30** in a slightly twisted state, the second bosses **31b** and **32b** pass through the first inclined portions **41c** and **42c**.

When the first bosses **31a** and **32a** are located in the fourth flat portions **41h** and **42h**, and the second bosses **31b** and **32b** are located in the second flat portions **41d** and **42d**, the intermediary transfer belt **8** is kept in pressed contact with the photosensitive drums **1a** to **1d** under a predetermined force.

In the manner described above, the intermediary transfer unit **30** is attached to the main body of the image forming apparatus **100**.

When the intermediary transfer unit **30** is pulled out of the main body of the image forming apparatus **100**, the first bosses **31a** and **32a** and the second bosses **31b** and **32b** operate the other way around than described above.

In this embodiment, as described above, the first inclined portions **41c** and **42c** are formed asymmetrically with each other in the unit width direction. Likewise, the second inclined portions **41e** and **42e** are formed asymmetrically with each other in the unit width direction, and the third inclined portions **41g** and **42g** are formed asymmetrically with each other in the unit width direction. Thus, the intermediary transfer unit **30** is attached and detached while being twisted slightly, and this produces an adequate sliding load between the intermediary transfer unit **30** and the guide rails **41a** and **42a**. This prevents the first bosses **31a** and **32a** and the second bosses **31b** and **32b** on the intermediary transfer unit **30** from hitting vigorously the first inclined portions **41c** and **42c**, the second inclined portions **41e** and **42e**, and the third inclined portions **41g** and **42g** of the guide rails **41a** and **42a**, and it is thus possible to prevent breakage of the intermediary transfer unit **30** and the guide rails **41a** and **42a**, and to prevent loud impact noise.

A time lag between the near side (the guide rail **41a** side) and the far side (the guide rail **42a** side) of the apparatus can be introduced in the timing with which the first bosses **31a** and **32a** and the second bosses **31b** and **32b** hit the first inclined portions **41c** and **42c**, the second inclined portions **41e** and **42e**, and the third inclined portions **41g** and **42g**, and this helps prevent loud impact noise more effectively.

As described above, the first inclined portions **41c** and **42c** are arranged at mutually different positions in the unit attachment-detachment direction (the direction indicated by arrows AA'). Likewise, the second inclined portions **41e** and **42e** are arranged at mutually different positions in the unit attachment-detachment direction, and the third inclined portions **41g** and **42g** are arranged at mutually different positions in the unit attachment-detachment direction. Thus, a time lag between the near side and the far side of the apparatus can easily be introduced in the timing in which the first bosses **31a** and **32a** and the second bosses **31b** and **32b** move up and down, and this allows easy twisting of the intermediary transfer unit **30**.

As described above, at least the third inclined portions **41g** and **42g** are formed asymmetrically with each other in the unit width direction. The intermediary transfer unit **30** tends to accelerate more easily when it is attached than when it is pulled out, and the first bosses **31a** and **32a** tend to hit vigorously the third inclined portions **41g** and **42g** in an end part of the guide rails **41a** and **42a** on the downstream side (in the direction indicated by arrow A) in the unit attachment direction. Thus, forming the third inclined portions **41g** and **42g**, which is provided in an end part of the guide rails **41a** and **42a** in the downstream side in the unit attachment direction, asymmetrically with each other is particularly effective.

15

Second Embodiment

In a second embodiment of the present disclosure, as shown in FIGS. 10 and 11, the first inclined portions **41c** and **42c** are formed with mutually different inclination angles, so are the second inclined portions **41e** and **42e**, and so are the third inclined portions **41g** and **42g**. Specifically, the first inclined portion **41c** is formed with an inclination angle smaller than that of the first inclined portion **42c**. Likewise, the second inclined portion **41e** is formed with an inclination angle smaller than that of the second inclined portion **42e**, and the third inclined portion **41g** is formed with an inclination angle smaller than that of the third inclined portion **42g**.

When the intermediary transfer unit **30** is attached to the main body of the image forming apparatus **100**, since the first inclined portion **41c** is formed with an inclination angle smaller than that of the first inclined portion **42c**, the first boss **31a** moves downward at lower speed than the first boss **32a**. Thus, with the intermediary transfer unit **30** in a slightly twisted state, the first bosses **31a** and **32a** pass through the first inclined portions **41c** and **42c**. Since the second inclined portion **41e** is formed with an inclination angle smaller than that of the second inclined portion **42e**, the first boss **31a** moves upward at lower speed than the first boss **32a**. Thus, with the intermediary transfer unit **30** in a slightly twisted state, the first bosses **31a** and **32a** pass through the second inclined portions **41e** and **42e**.

Since the third inclined portion **41g** is formed with an inclination angle smaller than that of the third inclined portion **42g**, the first boss **31a** moves downward at lower speed than the first boss **32a**. Thus, with the intermediary transfer unit **30** in a slightly twisted state, the first bosses **31a** and **32a** pass through the third inclined portions **41g** and **42g**. Since the first inclined portion **41c** is formed with an inclination angle smaller than that of the first inclined portion **42c**, the second boss **31b** moves downward at lower speed than the second boss **32b**. Thus, with the intermediary transfer unit **30** in a slightly twisted state, the second bosses **31b** and **32b** pass through the first inclined portions **41c** and **42c**.

When the intermediary transfer unit **30** is pulled out of the main body of the image forming apparatus **100**, the first bosses **31a** and **32a** and the second bosses **31b** and **32b** operate the other way around than described above.

In other respects in terms of structure and in terms of the operation for attaching and detaching the intermediary transfer unit **30**, the second embodiment is similar to the first embodiment described previously.

In this embodiment, as described above, the first inclined portions **41c** and **42c** are formed with mutually different inclination angles. Likewise, the second inclined portions **41e** and **42e** are formed with mutually different inclination

angles, and the third inclined portions **41g** and **42g** are formed with mutually different inclination angles. Thus, a difference between the near side and the far side of the apparatus can easily be introduced in the speed or timing with which the first bosses **31a** and **32a** and the second bosses **31b** and **32b** move up and down, and this allows easy twisting of the intermediary transfer unit **30**.

In other respects in terms of benefits, the second embodiment is similar to the first embodiment described previously.

The embodiments disclosed herein should be understood to be in every respect illustrative and not restrictive. The scope of the present disclosure is not defined by the description of embodiments given above but by the appended claims, and encompasses any modifications made in the sense and scope equivalent to those of the claims.

For example, the above description deals with examples where the present disclosure is applied to a color printer, this is not meant to limit the application of the present disclosure. Needless to say, the present disclosure is applicable to a variety of image forming apparatuses, such as monochrome printers, color copiers, monochrome copiers, and facsimile machines, that incorporate a unit attachment-detachment mechanism including a unit and a guide rail.

Although the above embodiments deal with examples where an intermediary transfer unit is used as a unit that is attachable to and detachable from an apparatus main body, any unit other than an intermediary transfer unit (for example, a drum unit, a developing unit, or a fixing unit) may instead be used.

Although the above embodiments deal with examples where three pairs of inclination portions (the first inclined portions **41c** and **42c**, the second inclined portions **41e** and **42e**, and the third inclined portions **41g** and **42g**) are provided in the guide rails **41a** and **42a** and these three pairs of inclined portions each have inclined portions formed asymmetrically with each other in the unit width direction, this is not meant to limit the implementation of the present disclosure. At least one pair of inclined portions has to have inclined portions formed asymmetrically with each other in the unit width direction.

Although the above embodiments deal with examples where three pairs of inclination portions (the first inclined portions **41c** and **42c**, the second inclined portions **41e** and **42e**, and the third inclined portions **41g** and **42g**) are provided in the guide rails **41a** and **42a**, this is not meant to limit the implementation of the present disclosure. At least one pair of inclined portions has to be provided in the guide rails **41a** and **42a**.

Any combination of features from different ones of the embodiments and modified examples described above falls within the technical scope of the present disclosure.

What is claimed is:

1. A unit attachment-detachment mechanism, comprising, a unit attachable to and detachable from an apparatus main body in a horizontal direction; and

a pair of guide frames provided on the apparatus main body and slidably supporting a pair of side faces of the unit parallel to an attachment-detachment direction of the unit and arranged respectively at both sides in a unit width direction perpendicular to the attachment-detachment direction, the pair of frames being arranged at a predetermined distance from each other in the unit width direction,

wherein

the pair of frames respectively include guide rails which slidably support the side faces of the unit, the side faces respectively have formed thereon engagement projections that engage with the guide rails, the pair of guide rails has formed therein at least a pair of inclined portions along which the engagement projections move in an up-down direction, and

the pair of inclined portions is formed asymmetrically with each other in the unit width direction.

2. The unit attachment-detachment mechanism of claim 1, wherein

the pair of inclined portions is arranged at mutually different positions in the attachment-detachment direction.

3. The unit attachment-detachment mechanism of claim 1, wherein

the pair of inclined portions is formed with mutually different inclination angles.

4. The unit attachment-detachment mechanism of claim 1, wherein

the pair of inclined portions is provided in an end part of the pair of guide rails on a downstream side in a unit attachment direction.

5. The unit attachment-detachment mechanism of claim 1, wherein

the unit is an intermediary transfer unit having an intermediary transfer belt.

6. An image forming apparatus comprising the unit attachment-detachment mechanism of claim 1.
